UNITED STATES PATENT OFFICE.

ANDRÉ VIGNEAU, OF ST. OUEN, FRANCE, ASSIGNOR TO ANCIENS ETABLISSEMENTS SIEGEL & STOCKMAN REUNIS SOCIETE ARANyme, OF ST. OUEN, FRANCE, A CORPORATION OF FRANCE.

DESIGN FOR A HEAD FOR MANNEQUIN OR SIMILAR ARTICLE.

Application filed December 12, 1928. Serial No. 29,244. Term of patent 7 years.

To all whom it may concern:

Be it known that I, ANDRÉ VIGNEAU, a citizen of the Republic of France, residing at St. Ouen (Seine), France, have invented a new, original, and ornamental Design for Head of Mannequin or Similar Article, of which the following is a specification, reference being had to the accompanying drawing, forming part thereof.

I claim:

The ornamental design for a head for mannequin or similar article, as shown.

In testimony whereof I have signed my name to this specification.

ANDRÉ VIGNEAU.
